United States Patent Office

Des. 202,821

Patented Nov. 9, 1965

202,821

LITTER BAG

Richard A. Waldinger, Flushing, N.Y., assignor to Progress Heat Sealing Co., Inc., New York, N.Y., a corporation of New York

Filed June 1, 1964, Ser. No. 30,228

Term of patent 14 years

(Cl. D58—2)

FIG. 1

FIG. 2

FIG. 4

FIG. 3

FIGURE 1 is a front elevational view of a litter bag, showing my new design;

FIGURE 2 is a top plan view thereof;

FIGURE 3 is a rear elevational view thereof; and

FIGURE 4 is a side elevational view thereof.

I claim:

The ornamental design for a litter bag, as shown.
